[57] CLAIM

The ornamental design for a golf grip, as shown and described.

DESCRIPTION

FIG. 1 is a left side elevational view of a golf grip of the present invention;

FIG. 2 is an enlarged top plan view thereof;

FIG. 3 is a left side elevational view of FIG. 2;

FIG. 4 is a front elevational view of FIG. 2;

FIG. 5 is a right side elevational view of FIG. 2;

FIG. 6 is a rear elevational view of FIG. 2; and,

FIG. 7 is a bottom plan view of FIG. 2.

The broken line showing on FIG. 1 is for illustrative purposes only and forms no part of the claimed design.
